UNITED STATES PATENT OFFICE.

KENNETH M. CHAPMAN, OF LAS VEGAS, TERRITORY OF NEW MEXICO.

DESIGN FOR A BOX.

SPECIFICATION forming part of Design No. 36,621, dated November 10, 1903.

Application filed October 3, 1903. Serial No. 175,701. Term of patent 7 years.

To all whom it may concern:

Be it known that I, KENNETH M. CHAPMAN, a citizen of the United States, residing at Las Vegas, in the county of San Miguel and Territory of New Mexico, have invented a new, original, and ornamental Design for Boxes, of which the following is a specification.

This invention relates to an ornamental design for a box, illustrated in the accompanying drawing, which shows a perspective view of a box embodying the features of the design.

What is claimed as new is—
The ornamental design for a box, as shown.
In testimony whereof I affix my signature in presence of two witnesses.

KENNETH M. CHAPMAN.
